UNITED STATES PATENT OFFICE

PAUL ZIENTEK, OF SALZBURG, AUSTRIA

RAIL JOINT

Application filed September 25, 1930, Serial No. 484,391, and in Austria September 13, 1930.

This invention relates to a joining for rails of the type in which ridges attached to the first-plates connect the rail heads at the joint. Hitherto the outer ridges were longer than the inner ones but, in accordance with the present invention the outer ridge is shorter than the inner, so that at the point at which the inner ridge terminates the outer portion of the rail head participates in the taking up of the lateral wheel thrust. Further, in accordance with the invention, the outer ridge is not extended to the web of the rail but is kept narrower, whereby the strength of the joint is likewise increased. The inner ridge is graded or bevelled off, so that sufficient supporting surface is provided for the wheel on passing the joint. In order to render the joint according to the invention suitable also for the sleeve type of fish-plates which embrace the rails these fish-plates are so divided that the ridges are provided on separate flat bars connected to the fish-plate, so that the fish-plates are capable of being manufactured by rolling.

Several forms of construction of the invention are shown, by way of example, in the accompanying drawings, in which:-

Fig. 1 is a view of a rail-point in accordance with the invention, with L-shaped fish-plates.

Fig. 1^a is a detail section showing a slight modification.

Fig. 2 is a section of the same taken on the line A—B of Fig. 1.

Fig. 3 is a side elevation looking from the outside of the rail in direction of the arrows in Figs. 1 and 2.

Fig. 4 shows the configuration of the ridge in the case of joints on a curve.

Fig. 5 shows a modified form of ridge.

Fig. 6 shows a modification of the fish-plates.

Fig. 7 shows the construction of the base plate for two sleepers.

Fig. 8 is a section on the line C—D of Fig. 9 of a rail joint construction in accordance with the invention with profile-section fish-plates.

Fig. 9 is a plan of the joint shown in Fig. 8.

Figs. 10 and 11 show in section two modified forms of these fish-plates.

The rail-ends 1 are connected together by means of an outer L-shaped fish-plate 2 and a similarly L-shaped inner fish-plate 3 the inner surfaces of which are applied to the side surfaces of the rail-webs. The outer fish-plate 2 is provided with a gib or strip 5 the upper edge of which is flush with the running surface of the rail and which lies against the heads 7 of the rails, and this fish-plate is connected to the inner fish-plates by means of bolts 6. At the joint between the rails the fish-plates are provided with ridges extending between the heads 7 of the rails, but the ridge 8 of the outer fish-plate is shorter, measured in the direction of the axis of the rail, than the ridge 9 of the inner fish-plate, so that at the point at which the ridge of the inner fish-plate terminates the outer portion of the rail-head itself takes up the lateral thrust of the wheels. On the other hand the ridge 8 does not extend to the web of the rail, so that a portion of the head runs through to the end of the rail. The ridge 9 of the inner fish-plate 3 which projects between the heads of the rails is off-set at 10 at right angles to the axis of the rail for the full cross-section of the head of the rail, which serves the purpose of giving the wheel sufficient bearing surface during the traversing of the gaps between the ridge and the head of the rails. The distance between the steps 10 is made greater than the length of the outer ridge 8, so that in the region of the steps 10 also the outer portion of the head of the rail is able to bear a share of the lateral wheel-thrust.

The horizontal portions of the fish-plates are provided with longitudinal holes 11 through which the bolts 12 are passed for the attachment of the fish-plates to the base-plate 13 in which recesses 14 are provided to receive the heads 15 of the bolts 12. The employment of nuts and bolts is preferable to that of cap screws, since the former are not subjected to shearing strain. The same purpose can be achieved by the insertion of the heads of the bolts in reversed T-shaped grooves 14', as shown in Figure 1^a.

Instead of the known type of set-screws for the fish-plates against lateral displacement there may be employed clamping plates 16 with an oblique outer surface 18 adapted to be supported against a similarly oblique projection 17 on the base-plate, while the other clamping surface 19 of the clamping plates presses against the fish-plate. The bolts 20 enable the required pressure to be exercised on the clamping plate, and can at the same time serve for the attachment of the base-plate to the sleeper 21.

In the case of joints on a curve of the line the ridge 8 on the outer rail is omitted, while the inner ridge 9 can remain unaltered (Fig. 4). Instead of omitting the ridge 8 the outer gib 5 can be dispensed with in joints on a curve.

The corners 22 and 23 of the ridge 9 and the corners 24 of the ridge 8 as also the corresponding corners of the material of the rails are preferably bevelled off, as shown in Fig. 5. Instead of the ridge 8 and the gib 5 being formed in one with the outer fish-plate 2 this gib and the adjoining portion of the fish-plate for the breadth of the ridge 8 can be made in a separate piece 25, as shown in Fig. 6; this piece 25 is likewise pressed against the rail by means of the bolts 6.

Any other kind of base-plate may be employed instead of that shown in Figs. 1-3 of the drawings. For the purpose of increasing the supporting effect of the base-plate the latter is provided with projections 26 disposed in the direction of the length of the rails. These projections are adapted to lie against the foot of the rail and are stiffened against the sleeper by means of ribs 27.

If, instead of a broad sleeper, two narrower sleepers 28 are employed, one under each rail-end, the base-plate acquires the form shown in Fig. 7. In this case also the projections 26 with the ribs 27 are provided, but can be omitted if desired.

Fish-plates of a cross-section adapted to fit round the lower portion of the rail ("sleeve fish-plates") may be employed in place of the L-shaped fish-plates, but fish-plates of this type, when provided with ridges in accordance with the present invention, would not be capable of being rolled. If the invention is to be used in connection with this type of fish-plate, and the latter at the same time to be capable of being rolled, the fish-plates must be divided as shown, in connection with a few examples, in Figs. 8-11.

As shown in Fig. 8 the fish-plate 30 consists of one piece the cross-section of which is adapted to the configuration of the profile of the lower portion of the rail and which extends up to the heads of the rails, whereby, however, the portion of the fish-plates in contact with the web of the rails is reduced to approximately half the thickness

of the remaining portions. The lateral portions of the fish-plate are completed by flat bars of which the inner, 31, carries the ridge 9, and the outer, 32, the ridge 8 and the gib 5. A shoulder 40 serves for the guidance and support of the bar 32. To ensure the correct position of the fish-plates on the base-plate it is sufficient to provide the clamping plates 33 which are tightened by means of the bolts 34. These clamping plates are strained between the outer edge of the fish-plates on the one hand and a ridge 35 on the base-plate 13 on the other hand. Instead of the cap screws shown in the drawing nuted bolts with their heads countersunk in the base-plate may be employed. The base-plate is secured to the sleeper 21 by means of the bolts 36. The bolts 36 may also be arranged between the clamping plates.

In the modification shown in Fig. 10 the chair-plate consists of two portions 37 and 38 which interlock beneath the foot of the rails by means of an S-shaped wedge 41 and of a similarly shaped groove, so that they are locked against mutual displacement. The locking can also be effected, as shown in Fig. 11, by the division of the horizontal portion of the chair-plate in the middle and the provision of the same with projecting ridges 39 adapted to fit into corresponding recesses in the base-plate 13. The rail joint is then completed by means of the flat bars 31 and 32, as shown in Fig. 8.

In all these forms of construction the basic principle of the invention is retained, that is to say the outer ridge 8 is kept shorter than the inner ridge 9. The latter, however, is provided, instead of a step 10, with an inclined surface 22, approximately as shown in Fig. 5.

Having thus described my invention, what I claim as new, and desire to secure by Letters Patent of the United States, is:—

1. A rail joint comprising a base-plate being secured to the sleeper, clamping plates adapted to be secured to the base-plate, fish-plates being strained between the clamping plates and the rails, ridges connected to the fish-plates and projecting between the heads of the rails at the points of their abutment, the inner ridge being longer as measured in the direction of the axis of the rail than the outer ridge, the length of the outer portion of the inner ridge being greater than the length of its inner portion.

2. A rail joint comprising a base-plate being secured to the sleeper, clamping plates adapted to be secured to the base-plate, fish-plates being strained between the clamping plates and the rails, ridges connected to the fish-plates and projecting between the heads of the rails at the points of their abutment, the length of the outer portion of the inner ridge being greater than the length of its inner portion, and the length of this inner

portion being greater than the length of the outer ridge, all as measured in the direction of the axis of the rail.

3. A rail joint comprising a base-plate being secured to the sleeper, clamping plates adapted to be secured to the base plate, fish-plates being strained between the clamping plates and the rails, ridges connected to the fish-plates and projecting between the heads of the rails at the points of their abutment, the length of the outer portion of the inner ridge being greater than the length of its inner portion, and the length of this inner portion being greater than the length of the outer ridge, all as measured in the direction of the axis of the rail, and the outer ridge not extending to the web of the rail.

4. A rail joint comprising a base-plate being secured to the sleeper, clamping plates adapted to be secured to the base-plate, fish-plates being strained between the clamping plates and the rails, ridges connected to the fish-plates and projecting between the heads of the rails at the points of their abutment, the inner ridge being longer as measured in the direction of the axis of the rail than the outer ridge, the inner ridge being set off in a right angle to the direction of the axis of the rail so as to form an outer and an inner portion in the inner ridge, the length of the outer portion of the inner ridge being greater than the length of its inner portion, and the length of this inner portion being greater than the length of the outer ridge, all as measured in the direction of the axis of the rail, and the outer ridge not extending to the web of the rail.

5. A rail joint comprising a base-plate being secured to the sleeper, clamping plates adapted to be secured to the base-plate, L-shaped fish-plates held between the clamping plates and the rails and secured to the base-plate by means of nutted bolts the heads of which are countersunk in recesses on the underside of the base-plate, ridges connected to the fish-plates and projecting between the heads of the rails at the points of their abutment, the inner ridge being longer as measured in the direction of the axis of the rail than the outer ridge, the inner ridge being set off in a right angle to the direction of the axis of the rail so as to form an outer and an inner portion in the inner ridge, the length of the outer portion of the inner ridge being greater than the length of its inner portion, and the length of this inner portion being greater than the length of the outer ridge, all as measured in the direction of the axis of the rail, and the outer ridge not extending to the web of the rail.

6. A rail joint comprising a base-plate being secured to the sleeper, clamping plates adapted to be secured to the base-plate and provided with wedge surfaces adapted to be applied to corresponding surfaces on projec-

tions on the base-plate, L-shaped fish-plates held between the clamping plates and the rails and secured to the base-plate by means of nutted bolts the heads of which are countersunk in recesses on the underside of the base-plate, ridges connected to the fish-plates and projecting between the heads of the rails at the points of their abutment, the inner ridge being longer as measured in the direction of the axis of the rail than the outer ridge, the inner ridge being set off in a right angle to the direction of the axis of the rail so as to form an outer and an inner portion in the inner ridge, the length of the outer portion of the inner ridge being greater than the length of its inner portion, and the length of this inner portion being greater than the length of the outer ridge, all as measured in the direction of the axis of the rail, and the outer ridge not extending to the web of the rail.

7. A rail joint comprising a base-plate secured to the sleeper, clamping plates adapted to be secured to the base plate, chair-plates held between the clamping plates and the rails, ridges connected to the chair-plates and projecting between the heads of the rails at the points of their abutment, the inner ridge being longer as measured in the direction of the axis of the rail than the outer ridge, the corners of the inner ridge projecting into the head of the rail being bevelled off so as to form an outer and an inner portion in the inner ridge, the length of the outer portion of the inner ridge being greater than the length of its inner portion, and the length of this inner portion being greater than the length of the outer ridge, all as measured in the direction of the axis of the rail, and the outer ridge not extending to the web of the rail.

8. A rail joint comprising a base-plate secured to the sleeper, clamping plates adapted to be secured to the base-plate, chair-plates held between the clamping plates and the rails, ridges connected to the fish-plates and projecting between the heads of the rails at the points of their abutment, the inner ridge being longer as measured in the direction of the axis of the rail than the outer ridge, the inner ridge being set off in a right angle to the direction of the axis of the rail so as to form an outer and an inner portion in the inner ridge, the length of the outer portion of the inner ridge being greater than the length of its inner portion, and the length of this inner portion being greater than the length of the outer ridge, all as measured in the direction of the axis of the rail, and the outer ridge not extending to the rib of the rail, the corners of the outer and the inner portion of the inner ridge and the corners of the outer ridge which project into the head of the rail being bevelled off.

9. A rail joint comprising a base-plate secured to the sleeper, clamping plates adapted

to be secured to the base plate, L-shaped fish-
plates held between the clamping plates and
the rails and secured to the base-plate by
means of nutted bolts the heads of which are
5 countersunk in reversed T-shaped grooves in
the base-plate running in the direction of the
length of the rail, ridges connected to the fish
plates and projecting between the heads of
the rails at the points of their abutment, the
10 inner ridge being longer as measured in the
direction of the axis of the rail than the
outer ridge, the inner ridge being set off in a
right angle to the direction of the axis of the
rail so as to form an outer and an inner por-
15 tion in the inner ridge, the length of the outer
portion of the inner ridge being greater
than the length of its inner portion, and the
length of this inner portion being greater
than the length of the outer ridge, all as meas-
20 ured in the direction of the axis of the rail,
and the outer ridge not extending to the web
of the rail.

10. A rail joint comprising a base-plate se-
cured to the sleeper and carrying projections
25 stiffened by means of ribs which support the
foot of the rail beyond the base-plate, clamp-
ing plates adapted to be secured to the base-
plate, fish-plates held between the clamping
plates and the rails, ridges connected to the
30 fish-plates and projecting between the heads
of the rails at the points of their abutment,
the inner ridge being longer as measured in
the direction of the axis of the rail than the
outer ridge.

35 In testimony whereof I affix my signature.
PAUL ZIENTEK.
